UNITED STATES PATENT OFFICE.

LOUIS TISCH, OF NEW YORK, N. Y.

DESIGN FOR TRIMMING.

SPECIFICATION forming part of Design No. 21,834, dated September 6, 1892.

Application filed June 26, 1892. Serial No. 438,041. Term of patent 3½ years.

To all whom it may concern:

Be it known that I, LOUIS TISCH, a citizen of the United States, and a resident of New York, in the county of New York and State 5 of New York, have invented a certain new and useful Design for Gimp Trimmings, of which the following is a specification.

The figure represents a face view of a flat band gimp trimming, the cords and their loops 10 arranged according to my design.

The leading feature of my design consists in the representation of a zigzag half-twist cord A, and between its loops the loops of a cord B, and having the outer large loops of 15 each cord B provided with a secondary lat-

erally-laid looped cord B'. Across each row of loops is a straight longitudinal line D, as shown. The extreme rows of loops of each cord B' are represented with a connected corrugated cord C.

What I claim is—

The design for a flat band trimming herein described and shown.

Signed at New York, in the county of New York and State of New York, this 24th day of 25 June, A. D. 1892.

LOUIS TISCH.
